(57) **CLAIM**

The ornamental design for a charging dock as shown and described.

DESCRIPTION

FIG. 1 is a front, left-side, and top perspective view of a charging dock showing our new design;

FIG. 2 is a rear, right-side, and bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a another rear, right-side, and bottom perspective view of the charging dock shown in an alternate configuration;

FIG. 10 is a perspective view of the charging dock in a state of use with dot-dashed broken line environment; and,

FIG. 11 is a perspective view of the charging dock in another state of use with dot-dashed broken line environment.

The evenly dashed broken lines depict portions of the charging dock that form no part of the claimed design.

The dot-dashed broken lines in FIGS. 10 and 11 are for illustrating environment structure only and form no part of the claimed design.
